CRATE LIDDING MACHINE

Herbert E. Twomley, Riverside, Calif., assignor,
by mesne assignments, to Food Machinery Cor-
poration, a corporation of Delaware

Application August 10, 1934, Serial No. 739,275

4 Claims. (Cl. 1—10)

My invention relates to crate lidding machines and has particular reference to a machine for applying lids, or covers, to containers, wherein the covers are formed of a plurality of separate 5 boards, each individually secured to the container.

In the art of packing certain vegetables, fruits, and the like, it is common practice to fill containers, such as boxes or crates formed of wood, and to place these boxes in machines for 10 applying lids or covers thereto. Certain types of crates or containers now in general use for this purpose require that the covers be formed of individual strips of wood or slats, each of which is to be separately and individually secured to 15 the container. Even when the machines are adapted for the securing of covers to a particular kind of crate, (that is to a crate or container for a particular kind of goods), the crates or containers employed will vary considerably in size, and particularly in width, so that in order to properly space the individual cover slats over the 20 containers of different sizes, it is necessary to adjust the nail driving mechanism to evenly space the same to fit one size of container or to fit another size of container.

It is therefore an object of my invention to provide a machine for applying covers to containers in which the nailing mechanisms may be readily adjusted to fit different widths of 25 containers.

Another object of the invention is to provide a machine for applying covers to containers of varying widths, in which the nail driving mechanisms are mounted for movement relative to each 30 other and are provided with control means which when operated will evenly space the nail driving mechanisms throughout different widths to conform with different widths of boxes.

Another object of the invention is to provide a machine of the character set forth in which a plurality of nail driving mechanisms are provided for each end of the container or box to be covered and in which the nail driving mechanisms are mounted for movement toward and away from 45 each other to adapt them for varying widths of containers.

Another object of the invention is to provide a machine for applying covers to boxes in which individual groups of nailing mechanisms are provided for each of the cover boards and in which each of the groups is mounted for movement relative to the remaining groups and controlled to evenly space the groups in varying widths to adapt them for varying widths of containers.

Other objects and advantages will be apparent

from a study of the following specifications, read in connection with the accompanying drawings, wherein

Fig. 1 is an elevational view of a machine for applying individual slats as covers for containers; 5

Fig. 2 is a detail horizontal sectional view taken along line II—II of Fig. 1;

Fig. 3 is a detail vertical sectional view, taken along line III—III of Fig. 4, showing a portion of the machine illustrating the mounting and 10 operating means for the individual nailing mechanisms;

Fig. 4 is a detail front elevational view of the 15 nailing mechanisms and positioning means for the same for one end of the box or container; and

Fig. 5 is a detail sectional view taken along line V—V of Fig. 2.

Referring to the drawings, I have illustrated a machine for applying lids to boxes shown in 20 its entirety in Fig. 1, wherein the machine includes a suitable base A from which extends uprights B and C constituting vertical bearing members upon which a pressframe D is reciprocably mounted for movement toward and away 25 from a nailing table E upon which a box or container to be nailed may rest. A pair of nail driving heads F and G, one for each side of the machine, are reciprocably mounted upon the pressframe D for movement toward and away from 30 the nailing table E.

The general construction of the machine, including the base A, uprights B and C, nailing table E, pressframe D and nail driving heads F and G, is substantially identical with the corresponding parts of a box lidding machine shown in 35 my copending application Serial No. 739,276, filed August 10, 1934, in which the construction and operation of these parts is illustrated and described in detail.

For the purposes of this application it is deemed sufficient to state that the nailing table E comprises a substantially rectangular frame upon which is mounted a plurality of rollers 1 arranged upon axes extending forwardly and rearwardly 45 of the machine to constitute in effect a conveyor section from which boxes may be fed into the machine from the right-hand side of the machine, as shown in Fig. 1. The boxes so fed into the machine come to rest upon the rollers 1, the 50 extreme ends of the boxes or containers resting immediately above a pair of end rollers 3 and 4 at the right and left-hand ends of the machine, respectively, so that the rollers 3 and 4 constitute rigid supports or anvils upon which the box ends 55

may rest during the pressing and nailing operations to resist the forces exerted by pressing the cover members down into contact with the box ends and then nailing the same thereto.

5 The pressframe D comprises, briefly, a cross head 5 which interconnects a pair of forwardly extending brackets 6 and 7, these brackets being interconnected at the front end of the machine by a cross bar 8 so as to form a substantially rigid 10 structure with the brackets 6 and 7 aligned slightly within a vertical line extending from the rollers 3 and 4.

The bracket 7 is illustrated as having a horizontally extending leg 9 which constitutes a 15 bearing member upon which a plurality of nail chucks 10 are mounted. Similarly the bracket 6 constitutes the mounting for a plurality of nail chucks arranged on the opposite side of the machine so that when the press frame D is moved 20 downwardly upon a box the nail chucks will press the ends of the cover members down into contact with the ends of the box ready for the nailing operations.

The pressframe D is illustrated as being connected through a connecting bar 11 to a crankpin 12 mounted upon a sector gear 13 in the lower portion of the machine, the sector gear being arranged to be rotated through a suitable power mechanism to be applied to rotate a pinion 14 so that as the sector gear is rotated in a 25 counterclockwise direction the pressframe D will be drawn down to press the cover members into contact with the box ends, and when the sector gear is rotated in a clockwise direction the pressframe D will be lifted back to its normal elevated position, as shown in Fig. 1.

The power mechanism employed for the reciprocating movement of the pressframe D is more particularly described in my copending 40 application hereinbefore referred to, the operation thereof being under the control of an attendant operating the machine who has only to press a pedal 15 extending from the front of the machine to cause the sector gear 13 to be 45 rotated to complete the pressing operations.

The nail driving heads F and G, which are interconnected at their upper ends by a cross bar 16 and at their lower ends by a cross bar 17, which latter cross bar is coupled by means of 50 a connecting rod 18 to a crankpin 19 carried upon a crank 20 also mounted upon the sector gear 13 but arranged as described in my copending application hereinbefore referred to to be rotated independently of the movement of the 55 sector gear 13 so that when the pressframe D has been drawn down to press the cover members into contact with the box ends the movement of the crank 20 without rotating will likewise draw the nail driving heads F and G downwardly in synchronism with the pressframe, but when the pressing operation has been completed the crank 20 may then be rotated to further draw the nail driving heads F and G downwardly to force their nail driving plungers 21 through 60 the chucks 10 to drive the nails, completing the lidding operation.

This last movement of the nail driving heads F and G is accomplished by power derived from a motor M controlled by a second foot pedal 22 70 also mounted upon the front end of the machine under the manual control of the person operating the machine. Again the details of the mechanism for operating the nail driving heads F and G under the control of the pedal 22, are set forth 75 in detail in my copending application mentioned

hereinbefore, and it is not deemed necessary to repeat the same in this application except to point out that the operation of the machine is that a box placed upon the nailing table E will receive a cover by first downward movement of the pressframe D and nail driving heads F and G to perform the pressing operations and then the nail driving heads F and G will be further operated to drive the nails through the chucks to complete the nailing operations.

As will be understood by those skilled in this art, the crates, boxes or containers to be covered are most readily covered by means of three or more relatively thin strips of wood which are arranged across the top of the box in substantially even spacing, rather than to use covers which are already assembled of a plurality of strips connected together by means of cleats.

This is particularly true with products such as cantaloupes wherein the widths of the boxes for various types of cantaloupes will vary within considerably wide limits so that proper positioning of the three cover strips on one width of box would not conform with the proper spacing of the strips on boxes which are wider or narrower. For this purpose it is necessary to mount the nail driving mechanisms so that they can be shifted forwardly and rearwardly of the machine to adapt them for differently spaced cover strips.

In order to accomplish this result and to permit the ready shifting of position of the nail driving mechanisms, each of the nail driving mechanisms may be constructed as a unit including the chuck 10 which is adapted to receive and hold two nails together with a pair of nail driving rods or plungers 21 reciprocably mounted in the chucks 10. Thus by sliding the chucks 10 transversely of the machine the two nails carried thereby may be properly aligned in 40 any position to which it is desired to place one of the cover strips.

By referring particularly to Figs. 2, 3, 4 and 5, it will be observed that the chucks 10 include a casting 24 constituting the body of the nail chuck to which may be secured a pair of movable straps 25 held in place by means of springs 26, one for each of the nails employed in the chucks. The casting 24 is illustrated as having a tongue 27 (Figs. 2 and 4) extending laterally therefrom to be received in a groove 28 (Fig. 3) which extends longitudinally of the leg 9 on the pressframe bracket 7 so that the tongue 27 and groove 28 constitute a slide mounting for the entire chuck and nail plunger assembly. The nail chuck assembly is secured in place in the slot 28 by means of a backing plate 29 secured to the chuck 10 by bolts 30 so that the plate 29 and chuck assembly will move as a unit.

The nail punches for each of the chuck assemblies 10 are illustrated as having formed upon their upper ends enlarged heads 31 (Fig. 4) engaging the underneath side of a longitudinally extending plate 32 secured to the nail driving head G. A second longitudinally extending plate 33 may be provided having an angularly extending flange to engage the underneath side of the enlarged head 31 of the nail plungers so that while the nail plunger 31 may slide relative to the nail driving head 6 the plate 33 will prevent disengagement of the plungers from the head G.

By referring particularly to Figs. 2 and 3 it will be observed that the rearmost chuck 10 (that

is the chuck assembly nearest the uprights **B** and **C** of the machine) may be initially adjusted to any desired position, adapting it to the spacing desired between the rear side edge of the box and the rearmost cover strip, and when so adjusted it may be rigidly secured in place since irrespective of the width of the box this chuck will always be aligned in the proper position for securing the rearmost cover strip to the box. The remaining chuck assemblies, however, must be mounted so as to slide forwardly and rearwardly of the machine to properly space the other slats which are to be secured to the box, and in order to accomplish this sliding movement I provide a shaft **34** (Figs. 2 and 3) journaled near each of its ends in a bearing member **35** (Fig. 2) supported by longitudinally extending braces **36** mounted upon the pressframe **D**, each of the outer ends of the shaft **34** having a crankarm **37** rigidly secured thereto and extending downwardly therefrom. The crank **37** has connected thereto a link **38** the opposite end **39** of the link being secured to the backing plate **29** of the intermediate chuck assembly **10**. In like manner a link **40** connects to the outer end of the crank **37** and to the backing plate **29** of the foremost chuck assembly **10**.

By properly spacing the connection of the links **38** and **40** upon the crank **37**, it will be apparent that rotational movement of the crank **37** will slide both of the chuck assemblies, but will upon any given movement of the crank **37** slide the intermediate chuck assembly only one-half of the distance through which the foremost chuck assembly is moved. Thus by rotating the shaft **34** by means of a suitable handle **41** the intermediate chuck will be spaced a predetermined distance from the rearmost chuck assembly **10**, while, at the same time, the foremost chuck assembly will be spaced from the intermediate chuck assembly by an equal amount. The handle **41** is illustrated as operating adjacent to a quadrant **42** which is provided with a plurality of notches **43** into which a pawl **44** may be engaged, the spacing of the notches **43** along the quadrant being selected to conform with the proper spacing for a plurality of different widths of boxes encountered in the use of the machine.

Thus when a person operating the machine knows that a box of predetermined width is fed into the machine, he may move the handle **41** into the proper notch **43** to insure the proper spacing of the nail chuck assemblies for that particular sized box, while if the next box is of different width he may then move the handle **41** into the notch corresponding to that width of box.

Since the covers are to be formed of a plurality of separate strips or slats, some means should be provided to support these individual strips upon their chuck assemblies immediately before and during the pressing and nailing operations, and to accomplish this I provide slat-holding mechanisms for each of the chucks. These slat-holding mechanisms are particularly illustrated in Figs. 2 and 5 as comprising a pair of short metal plates **45** and **46** spaced from each other by suitable spacing blocks **47**.

Between the plates **45** and **46** are a pair of slat-engaging dogs **48** and **49**, these dogs being pivoted upon suitable shafts **50** extending through the plates **45** and **46**.

By referring particularly to Fig. 5 it will be observed that the dog **48** has a slat-holding point or edge **51** formed thereon extending toward the front of the machine, while a similar edge **52** is

formed upon the dog **49**, and that the dog **49** is normally urged by means of a spring **53** toward the dog **48**. Thus the slats may be placed in the machine in groups of three by having the operator of the machine take up a group of three slats piled one above the other and manually placing this group in the machine under the rearmost nail chucks, as indicated in dotted lines **54** in Fig. 5. Then as the operator drags his hand forwardly of the machine, he will move this group of slats forwardly along the under surface of the plates **45** and **46**. As the group of slats is thus manually moved forwardly, the topmost slat will engage the dog **48** and swing the same about its pivot so that the top slat will slide along the lower surface of the plates **45** and **46** until the rear edge of the slat has passed the dog **48**. The dog **48** will then fall behind the uppermost slat. At the same time the forward edge of the topmost slat will engage the knife-edge **52** of the front dog **49** and will swing the dog in a clockwise direction until the dog **48** has fallen behind the slat at which time the spring **53** will swing the dog **49** rearwardly of the machine to press the topmost slat back against the dog **48**. A stop pin **55** is arranged immediately behind the dog **48** so that the spring **53** will always move the slat back to a predetermined position. Similarly, stop pins **56** and **57** may be provided to engage an extending ear **58** on the dog **49** and limit the movement of this dog during its retracting and slat-engaging movements.

It will be observed from an inspection of Fig. 5 that the dogs **48** and **49** extend below the plates **45** and **46** a distance substantially less than the thickness of one of the slats so that when the topmost slat has been engaged by its dog the remaining slats may be drawn forwardly of the machine until the second slat is engaged by the dogs **48** and **49** of the intermediate chuck assembly **10** which being constructed in the same manner will grasp the second slat and allow the third or lowermost slat to be pulled forwardly for engagement by the dogs **48** and **49** of the slat-holding mechanism on the front chuck assembly **10**.

The entire chuck grasping and holding mechanism is secured upon a vertically extending bar **59** slidably mounted in a box-like housing **60** constituting a portion of a laterally extending arm **61** which may be attached to or formed integrally with a backing plate **29** of the chuck assembly with which it is associated. A pair of springs **62** engaging pins **63** and **64** normally urges the slat-holding mechanism downwardly so that the slats may be inserted in the machine without interference with the chuck portions of the chuck assemblies **10**, but when the press-frame **D** moves downwardly to press the slats into engagement with the ends of the box the slat-holders may be retracted upwardly to automatically align themselves with the alignment taken by the slats as they are pressed into engagement with the box.

In order to insure a relatively flat surface from which all of the slats may be drawn in placing them into the machine, I prefer to stagger the slat-holding mechanisms, as indicated particularly in Fig. 2, wherein the slat-holding mechanism associated with the foremost chuck assembly and that associated with the rearmost chuck assembly are in vertical alignment with each other, while the slat-holding mechanism associated with the intermediate chuck assembly

bly is spaced laterally of the first-named slat-holders.

It will also be observed that the length of the plates 45 and 46 for each of the slat-holding mechanisms is such that they slightly overlap the plates of the adjacent chuck holding assemblies, thus providing a continuous horizontal line against which the slats may be held during the time they are placed in the machine.

10 If desired, a stop rod 65 may be provided upon the rearmost chuck assembly to constitute a positive stop against which the operator may place all of the slats prior to drawing them forward for distribution to the several slat-holders.

15 As is illustrated particularly in Fig. 2, identical constructions of slat-holders and chuck assemblies are provided upon opposite sides of the machine so that the slats will be engaged and held at both their ends and upon the movements 20 of the pressframe D and nail driving heads F and G both ends of each of the slats will be nailed to the box or container upon which the machine operates.

The machine constructed in accordance with 25 the foregoing description, operates as follows: The operator of the machine will take a group of three slats, place them at the rear of the machine under the rearmost chucks, and draw the same forwardly to cause the dogs 47 and 48 30 to grasp and hold one of these slats immediately below each of the chucks. He then draws a box into the machine, across the rollers 1 of the nailing table E, until the nailing table is properly centered beneath the pressframe D and the 35 nail driving heads F and G. He then notes the size of the box which has been drawn into the machine, and if it is different in width from the box which has been previously nailed in the machine, he grasps the handle 41 of the shaft 40 34 and moves this handle to the proper position to accurately and equally space the slats to fit the new size of box.

It will be understood by those skilled in the art that in most instances the difference in the 45 width of the box will not require differences in the width of the slats, but will merely require the spacing of the slats closer together or further apart in order to have the slats adequately cover the upper face of the box for the 50 purpose of holding the contents within the box. Thus the rearmost nail chuck may remain in the same position irrespective of the width of the box which is to be lidded, the rearmost slat being spaced the same distance from the side 55 edges of the box irrespective of the size of the box. Thus it is only necessary to move the middle slat a predetermined distance away from the rearmost slat and to move the foremost slat a predetermined distance away from the middle slat 60 until the forward edge of the forward slat is aligned at approximately the same distance from the front side of the box as the rearmost slat is placed from the rear of the box. This arrangement will space the slats equal distances 65 apart across the box.

The operator may then cause the machine to 70 perform its function of pressing the lids down into place upon the contents of the box until the ends of the slats contact the ends of the box ready for nailing, and then nail the slats to the box ends. This is accomplished by the operator's pressing on the pedal 15 which operates the motor M to rotate the sector gear 13 until the connecting bar 11 draws the pressframe with 75 the nail chucks downwardly toward the box,

which is now resting on the nailing table E, until the slat ends have been pressed down into contact with the ends of the box. The operator then steps upon the pedal 22, which causes the motor M to draw the connecting rod 18 downwardly to draw the nail driving heads F and G down, to press the nail punches through the chucks to drive the nails through the ends of the slats into the box ends to secure the slats to the box. After the nailing operation is complete, the nail driving heads E and F and the pressframe may be elevated to free the box, allowing the box to be moved out of the machine and the operator then inserts three more slats, ready for the reception of the next box.

15 It will therefore be apparent that I have provided a mounting for the nail chuck assemblies for machines of the character set forth, which will permit the same to be readily adjusted to any desired position to accommodate any one of 20 the various widths of box to be operated upon by the machine, while, at the same time holding mechanism for the individual strips or slats forming the covers of boxes may be readily placed in the machine, and by the movement of 25 the chuck assemblies be accurately aligned in the proper and evenly spaced positions necessary to adapt them for any width of box.

It will also be apparent that while I have described the machine and its operating mechanism 30 as particularly adapted to apply covers to boxes, the nail chuck and nail driving mechanism assemblies, together with the slat-holding assemblies, may readily be adapted to the manufacture 35 of boxes, crates, and the like.

While I have shown and described the preferred 35 embodiment of my invention, I do not wish to be limited to any of the details of construction shown herein, except as defined in the appended claims.

I claim:

1. In a machine for applying a series of wood strips as a cover to a box, a nailing table for supporting a box ready to receive said strips, a nailing head for each end of said box extending across said nailing table in alignment with the 45 ends of a box on said nailing table; nail driving units associated with each of said nailing heads, one for each of the strips employed to cover a single box, means fixedly mounting one of said nail driving units on each of said heads in a 50 predetermined alignment relative to the rear of said nailing table to nail the rearmost strip in predetermined fixed relation to the rear side of said box, means mounting the others of said nail driving units for sliding movement relative to said fixed nailing units, a rotatable shaft extending between said nailing heads and having an arm thereon for each of said nailing heads, said arms being rigidly attached to said shaft for rotation therewith, a separate link connecting each of said 55 sliding nail driving units associated with each of said heads with the arm associated with the respective head, and engaging said arm at such distances from said shaft that movement of said arm in response to rotation of said shaft will move said sliding nail driving units relative to said fixed unit but maintaining equal spacing between all of the nail driving units associated with each of said heads, and manual means for 60 rotating said shaft to adjust the position of said nail driving units to adapt them to nail slats at 65 equal distances from each other across a box in accordance with the width of said box.

2. In a machine for applying a series of wood strips as a cover to a box, a nailing table for supporting a box ready to receive said strips, a 75

- nailing head for each end of said box extending across said nailing table in alignment with the ends of a box on said nailing table; nail driving units associated with each of said nailing heads,
- 5 one for each of the strips employed to cover a single box, means fixedly mounting one of said nail driving units on each of said heads in a predetermined alignment relative to the rear of said nailing table to nail the rearmost strip in
- 10 predetermined fixed relation to the rear side of said box, means mounting the others of said nail driving units for sliding movement relative to said fixed nailing units, a shaft extending between said nailing heads and having a lever
- 15 thereon for each of said nailing heads; a separate link connecting each of said sliding nail driving units associated with each of said heads with the lever associated with the respective head, and engaging said lever at such distances from
- 20 said shaft that movement of said lever will move said sliding nail driving units relative to said fixed unit but maintaining equal spacing between all of the nail driving units associated with each of said heads, and manually operable means for
- 25 moving said shaft to any one of a plurality of positions to equally space said nail driving units to drive nails through slats equally spaced across the width of any one of a plurality of boxes of different widths, and means associated with said
- 30 manual means for fixing the location of said manual means when said nail driving units are adjusted for boxes of any one of a plurality of widths.
3. In a machine for applying a series of wood
- 35 strips as a cover to a box, a nailing table for supporting a box ready to receive said strips, a nailing head for each end of said box, extending across said nailing table in alignment with the ends of a box on said nailing table, nail driving
- 40 units associated with each of said nailing heads, each supporting one of said strips, means fixedly mounting one of said nail driving units on each of said heads in a predetermined alignment relative to the rear of said nailing table to nail the
- 45 rearmost strip in predetermined fixed relation, to the rear side of said box, means mounting the others of said nail driving units for sliding movement relative to said fixed nail driving unit, a shaft extending between said nailing heads, a
- separate link connecting each of said sliding nail driving units associated with each of said heads with the lever associated with the respective head, engaging said lever at such distances from said shaft that movement of said lever will move said sliding nail driving units relative to said fixed nail driving unit but maintain equal spacing between all of said nail driving units associated with each of said heads, and a handle on said shaft by which said shaft may be rotated to any one of a plurality of positions to equally space the said strips equal distances from each other across a box in accordance with the width of said box.
4. In a machine for applying a series of wood
- 15 strips as a cover to a box, a nailing table for supporting a box ready to receive said strips, a nailing head for each end of said box, extending across said nailing table in alignment with the ends of a box on said nailing table, nail driving
- 20 units associated with each of said nailing heads, each supporting one of said strips, means fixedly mounting one of said nail driving units on each of said heads in a predetermined alignment relative to the rear of said nailing table to nail
- 25 the rearmost strip in predetermined fixed relation, to the rear side of said box, means mounting the others of said nail driving units for sliding movement relative to said fixed nail driving unit, a shaft extending between said nailing
- 30 heads, a separate link connecting each of said sliding nail driving units associated with each of said heads with the lever associated with the respective head engaging said lever at such distances from said shaft that movement of said lever will move said sliding nail driving units relative to said fixed nail driving unit but maintain equal spacing between all of said nail driving units associated with each of said heads, a handle on said shaft, and a quadrant mounted
- 35 stationarily relative to said shaft and having means thereon for engaging said handle in any one of a plurality of positions of said handle whereby an operator may move said handle to any one of said positions to adjust said nail
- 40 driving units to space the strips equal distances from each other across a box in accordance with the width of said box.

HERBERT E. TWOMLEY.
